CLAIM

The ornamental design for a magnetic connector, as shown and described.

DESCRIPTION

FIG. 1 is a bottom, side perspective view of a magnetic connector showing our new design;

FIG. 2 is top, side perspective view thereof;

FIG. 3 is a front view thereof;

FIG. 4 is a rear view thereof;

FIG. 5 is a left-side view thereof;

FIG. 6 is a right-side view thereof;

FIG. 7 is a bottom view thereof;

FIG. 8 is top view thereof;

FIG. 9 is a bottom, side perspective view of a second embodiment thereof;

FIG. 10 is top, side perspective view thereof;

FIG. 11 is a front view thereof;

FIG. 12 is a rear view thereof;

FIG. 13 is a left-side view thereof;

FIG. 14 is a right-side view thereof;

FIG. 15 is a bottom view thereof; and,

FIG. 16 is top view thereof.

The broken lines illustrate portions of the magnetic connector and form no part of the claimed design. The gray shading on a portion of the magnetic connector represents a metallic surface.
